TENT

Klaus E. B. Krutzikowsky, 4331 Lowell Ave., Chicago, Ill.

Filed Oct. 22, 1965, Ser. No. 87,750

Term of patent 14 years

(Cl. D88—3)

FIG. 1 is a front and end perspective view of a tent, showing my new design;

FIG. 2 is a front elevational view thereof on a reduced scale showing the door flap in partially open position, portions of the tent support members having been omitted for convenience of illustration; and

FIG. 3 is an end elevational view opposite to that shown in FIG. 1, the center tie member and stake having been omitted for convenience of illustration.

The rear wall of the tent opposite that shown in FIG. 1 is substantially plain and unornamented.

The broken line showings of the ground stakes are for illustrative purposes only.

I claim:

The ornamental design for a tent, as shown and described.
